UNITED STATES PATENT OFFICE.

THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

MAGAZINE FOR TYPOGRAPHICAL MACHINES.

1,338,627.

Specification of Letters Patent. Patented Apr. 27, 1920.

Application filed May 7, 1918. Serial No. 233,052.

To all whom it may concern:

Be it known that I, THOMAS S. HOMANS, a citizen of the United States, residing at Hempstead, L. I., in the county of Nassau 5 and State of New York, have invented new and useful Improvements in Magazines for Typographical Machines, of which the following is a specification.

The present invention relates to improvements in typographical machines, and more especially to those of the class shown in Letters Patent No. 436,532 granted September 16, 1890, to O. Mergenthaler.

In machines of this class, one or more 15 magazines are mounted on the machine for storing and holding the matrices to be used, such magazine or magazines being removable and thus exchangeable for other magazines to enable changes to be made in the 20 style or size of type to be produced. Heretofore, the magazines have all been made of a length sufficient to store enough matrices of any one character to meet the demands of rapid operators engaged in regular composition work, in consequence of which the 25 operations of removing and replacing such magazines, which are comparatively heavy and cumbersome for manual handling, have been difficult.

30 The primary object of the present invention is to facilitate the changing of matrices to enable the production of type of different sizes and styles. This object is accomplished by providing a novel and improved 35 magazine construction wherein the magazine is divided to form upper and lower sections, the upper section being adapted to remain on the machine in operative relation with the distributing mechanism while the 40 lower section, which contains the matrices, is removable and exchangeable for another similar magazine section containing the desired font of matrices, the lower section of the magazine thus serving for the storage of the 45 matrices while the upper section, which does not require removal and may remain in position on the machine, serves as a guide for conducting and directing the matrices from the distributing mechanism to the lower 50 matrix storing section of the magazine.

55 While the matrix storage capacity of the magazine will be reduced by dividing the magazine in the manner described, yet its capacity will be sufficient for certain requirements which call for small quantities of

matrices and frequent changes of fonts, such for example as in the case of making corrections or for job work. In carrying out the invention, each divided magazine composed of the upper and lower sections is 60 interchangeable with any of the standard or full length magazines, for which purpose one section of the divided magazine will hold the other section thereof in proper endwise relation thereto, thus avoiding the necessity 65 of providing special holding means on the machine to accommodate the divided magazines.

To these and other ends, the invention 70 consists in certain improvements, and combinations and arrangements of parts, all as will be hereinafter more fully described, the novel features being pointed out particularly in the claims at the end of the specification. 75

In the accompanying drawing:

Figure 1 is a perspective view of a divided magazine constructed in accordance with the present invention, the same being shown mounted on the machine. 80

Fig. 2 is a perspective view of the lower or matrix storage section of the magazine removed from the machine.

Fig. 3 is a perspective view similar to Fig. 1, showing the upper magazine section 85 in position on the machine, the lower matrix storage section of the magazine being removed.

Fig. 4 shows, in side elevation, the divided magazine mounted on the magazine 90 carrying frame or cradle.

Fig. 5 shows a portion of the magazine viewed from the side, illustrating one of the connections between the sections, whereby one magazine section holds the other 95 magazine section in position on the machine.

Similar parts are designated by the same reference characters in the several views.

Preferably, and as shown in the present 100 instance, the magazine comprises a lower matrix storing section A' and an upper section A². These sections of the magazine are complementary and they are preferably of the same general construction as the usual full 105 length magazines commonly employed in machines of this class, the top and bottom plates of each section being grooved to form channels which guide the matrices while they gravitate from the upper toward the 110

lower end of the magazine. The lower section A' is provided with escapements which control the delivery of the matrices to the assembling mechanism in the usual way, and 5 the upper end of the upper section A² is adapted to register with and receive matrices from the distributing mechanism in the same way that the usual full length magazines receive the matrices. It will be 10 understood that, when the upper and lower sections of the divided magazine are in position on the machine, the meeting ends of the sections will be so placed that the matrix guiding channels in one section will register 15 correctly with the matrix guiding channels in the other section.

The divided magazine may be mounted in different ways on the machine. In the present instance, the magazine is shown on a 20 mounting which is adapted to accommodate a single magazine, this mounting being of the same general construction as that shown and described in my prior Patent, No. 1,116,280, granted November 3, 1914. The 25 mounting comprises, generally, a cradle or frame B which is pivotally supported in the machine on an axis b whereby the magazine on this cradle may be swung into a forwardly and downwardly inclined position 30 in which position it will be operatively related to the assembling and distributing mechanisms, and, also, the magazine may be swung into a rearwardly and downwardly inclined position, the latter position of the 35 cradle facilitating removal of the divided magazine as a whole as well as facilitating application and removal of the usual full length magazines. The cradle is provided at each side with a stop B' arranged to co- 40 operate with the respective side of the upper magazine section A², thereby holding this upper magazine section in position on the cradle. The lower magazine section A', which contains the matrices and which is 45 removable independently of the upper section A², is, in the present instance, supported by the frame B, and it is held in proper longitudinal position on the machine by the upper magazine section A². Prefer- 50 ably, and as shown, the springs A⁴ which serve to connect the matrix retaining shutter A³ to the upper magazine section A² serve to hold the lower magazine section A' in proper endwise relation to the upper maga- 55 zine section A². The shutter A³ is similar to the shutter shown in my prior patent referred to and it serves to prevent spilling of the matrices from the upper end of the magazine when the latter is tilted to its rear- 60 wardly and downwardly inclined position. This shutter is connected to the upper magazine section A² by the leaf springs A⁴, these springs being fixed at A⁷ to the rear of the upper magazine section A², and the lower 65 ends of these springs are provided with

shoulders A⁵ which are so located that, when the lower magazine section A' is placed on the machine in proper relation to the upper magazine section A², these shoulders A⁵ will engage the forward edge of a cross-bar A⁶ 70 which is secured to the rear side of the removable magazine section A'. By this construction, the magazine mounting or cradle B may interchangeably receive the usual or standard full length magazines and also 75 divided magazines constructed in accordance with the present invention, the same holding means for the full length magazines serving to hold the upper magazine section A² in position, and the independently removable lower magazine section A' in turn 80 is registered with the upper magazine section by the frame B and it is held in proper endwise relation with the upper magazine section by the springs or equivalent holding 85 means carried by the upper magazine section A².

By dividing the magazine into upper and lower sections as hereinbefore described, the lower matrix storage section of the magazine may, with ease and facility, be removed and replaced by another corresponding section while the upper section remains in place on the machine, this operation being easily performed from the front of the machine by 90 grasping the handles at the opposite sides of the lower magazine section. Furthermore, any machine constructed to receive the usual or standard full length magazines may also receive the divided magazine without requiring any change in the machine for the reasons that the same means on the machine which holds the usual full length magazines also holds the divided magazine in place, and the lower magazine section is held in 95 proper endwise relation to the upper magazine section by means carried by or forming part of the upper magazine section. Of course, the upper and lower magazine sections may both be removed and the machine 100 will then be adapted to receive the usual or standard full length magazines.

I claim as my invention:

1. In a typographical machine, the combination with a magazine supporting frame, 115 of a magazine divided into upper and lower sections, means on the supporting frame for holding the upper magazine section in longitudinal position, and means on the upper magazine section for holding the lower mag- 120azine section from longitudinal separation relatively to the upper section.

2. In a typographical machine, a supporting frame having means for locating a one-piece removable matrix magazine thereon, in 125 combination with a magazine divided into upper and lower sections, the supporting frame having means thereon for holding the upper magazine section in proper longitudinal position thereon, and means contained 130

wholly on the upper magazine section for holding the lower magazine section from longitudinal separation relatively to the upper section when the lower section is placed 5 in position relatively to the upper section.

3. In a typographical machine, the combination with a magazine supporting frame, of a matrix magazine comprising upper and lower complementary sections adapted to fit 10 together end to end on said frame and to be registered vertically by said frame, and means carried by one of said sections to co-operate with the other section and thereby hold the magazine sections together in 15 proper endwise relation and thus prevent longitudinal separation of the sections.

4. In a typographical machine, the combination with a magazine supporting frame of a matrix magazine comprising complementary sections adapted to rest on and to be thereby registered by said frame, said magazine sections being adapted to fit together in endwise relation, and means carried by the upper magazine section and detachably co-

operative with the lower section to hold the 25 magazine sections together and against endwise separation independently of the magazine supporting frame.

5. In a typographical machine having a mounting to removably receive magazines 30 and means thereon to hold such magazines in operative position, a magazine divided to form upper and lower sections, the upper section being adapted to co-operate with said holding means whereby the upper section is 35 held in position on the mounting, and said upper section carrying longitudinal extensions to co-operate with the lower section, when the latter is placed in position, and thereby hold the latter from endwise separation 40 relatively to the upper section.

In testimony whereof I have hereunto set my hand in presence of two subscribing witnesses.

THOMAS S. HOMANS.
